UNITED STATES PATENT OFFICE.

NATHANIEL BUTTERFIELD, OF MONROE, WISCONSIN.

ROOF.

SPECIFICATION forming part of Letters Patent No. 274,265, dated March 20, 1883.

Application filed August 21, 1882. (No model.)

To all whom it may concern:

Be it known that I, NATHANIEL BUTTERFIELD, a citizen of the United States, residing at Monroe, in the county of Green and State 5 of Wisconsin, have invented a new and useful Portable Roof for Ricks and Sheds, of which the following is a specification, reference being had to the accompanying drawings, forming a part thereof.

10 The object of my invention is to furnish a cheap, easily-constructed, and portable roof for the protection of hay and grain and to be used as shedding. This object I attain by constructing after the method illustrated in the 15 accompanying drawings, in which—

Figure 1 is a horizontal under side view, showing details of construction. Fig. 2 is a perspective view, showing its position when in use.

20 The roof is made in sections, each section being in two parts, joined at the center by passing a bolt or other suitable device through the overlapping parts of the rafters, as at A in Fig. 1. Each half-section is made of three 25 or more rafters and two cross-ribs, C C, in Fig. 1, as a frame, and covered with lap-boarding G. At F ropes or wires are attached, to which weights are suspended, and by this

means the roof is kept in position as the stack settles. At E is a hole through the rafter, 30 through which the roof may be fastened to posts in making temporary sheds. At D one of the boards overlaps, so that when the roof is at an angle of from thirty degrees to forty-five degrees the roof is tight. The ribs C C, together with the rafters, separate the roof from the hay or grain, and so allow a free circulation of air.

I am aware that hinged or jointed roofs provided with anchoring devices are not new, and 40 such I do not broadly claim.

Having fully described my invention, what I desire to claim and secure by Letters Patent is—

A portable roof having the rafters B hinged 45 together at the top, and each provided with a bolt-hole at the bottom, for the purpose described, the guy-ropes F, and the longitudinal strips C, which allow ventilation under the covering-boards G, all substantially as and for 50 the purpose described.

NATHANIEL BUTTERFIELD.
